UNITED STATES PATENT OFFICE.

HORATIO READ, OF JERSEY CITY, NEW JERSEY.

SYRINGE.

SPECIFICATION forming part of Letters Patent No. 427,111, dated May 6, 1890.

Application filed August 5, 1887. Serial No. 246,238. (Model.)

To all whom it may concern:

Be it known that I, HORATIO READ, of Jersey City, in the State of New Jersey, have invented an Improvement in Syringes, of which 5 the following is a specification, reference being had to the accompanying drawings, forming a part of the same.

The invention consists in the construction, combination, and arrangement of parts, here- 10 ro after described and claimed.

In the following drawings, Figure 1 is a perspective view of an ordinary syringe having my improvement attached thereto. Fig. 2 is 15 a vertical section of the auxiliary bulb dis- connected.

A represents the ordinary compressible bulb usually employed in syringes. It is made of rubber or other suitable substance and used in connection with the usual inlet and outlet 20 tubes and valves.

B is my auxiliary bulb, and is composed of flexible material, preferably of rubber. It is shown in the drawings as oval-shaped; but it will be readily seen that other forms of construction may be employed—such as cylindrical, spherical, &c.—without changing the 25 utility of my invention.

C is the usual tube through which the liquid flows from the vessel wherein it is contained to bulb A, and is provided with the ordinary induction-valve.

D is the connecting-tube between bulbs A and B, having placed in it the usual education-valve.

35 Running through the center of the hollow bulb B, and secured at one end thereof to the tube D and at the other end to the tube F, is a rigid core E, hollow at either end for a short space, the remainder thereof being solid. In 40 the hollow portion of said core at the tube D end thereof, and at a proper distance from the joint—say a quarter of an inch, though so much is not necessary—a hole b' is made in order to allow the liquid as it is forced 45 through the tube D and into the hollow portion of the core E, to gain entrance into the auxiliary bulb or chamber B. At the opposite end of core E, and in the same relative position, a similar hole b'' is made, but of 50 much smaller diameter than b'. Thus an outlet is provided for the liquid as it flows into and fills the bulb B, by means of the opening or hole b'', through which it flows to the outlet-tube F, and thence out of the dis- 55 charge-nozzle H. The opening or hole b',

being of larger diameter than the opposite hole b'', it will be seen that a larger flow of liquid will go into the chamber B than can flow from it through the smaller opening b'', thereby causing the liquid in the chamber 60 B to become compressed, which compression will suffice to continue the flow of the liquid through the opening b'', and consequently out of the discharge-nozzle, even after the supply through b' has ceased during the refilling of 65 bulb A. It is evident, however, that the holes b' b'' may each be made of the same size without departing from the spirit of my invention, and it is also evident that the opening or passage in each end of the core may 70 have two or more branch passages, which communicate with the interior of the bulb instead of one, as at present shown.

The operation of my improved syringe is substantially as follows: The contracting and 75 expanding of the bulb A causes it to become filled with the liquid. A second pressure closes the induction-valve and the liquid is forced through the tube D, and through that it passes into the hollow portion of core E, 80 and thence into bulb B, by means of inlet-opening b'. This opening b', being of a larger diameter than the outlet-opening b'', at the opposite end of the chamber B, as before explained, admits the liquid to the chamber 85 faster than it can escape therefrom. Thus the chamber is quickly filled, and the continued admission of liquid through the inlet b' causes a pressure in the chamber B, which is of sufficient force to cause the liquid to 90 flow out through the outlet-opening b'' in a steady stream while the bulb A is being recharged.

What I claim, and desire to secure by Letters Patent, is—

95 In a syringe, the combination, with the usual compressible suction-bulb, of the herein-described flexible auxiliary bulb, forming a part of and located in the discharge-tube, and provided with the core E traversing its 100 length, said core having openings at each end to admit the liquid into the bulb, and to allow it to pass out therefrom, the ingress-opening being larger than the egress-opening, substantially as described, and for the 105 purpose specified.

HORATIO READ.
